COMBINED BRUSH AND CONTAINER THEREFOR

Robert A. O'Neil, Pittsburgh, Pa., assignor to Fesco, Inc.,
New York, N.Y., a corporation of Delaware

Filed July 8, 1965, Ser. No. 86,086

Term of patent 14 years

(Cl. D58—17)

The conventional bristle portion of the bowl brush is concealed within the container.

I claim:

The ornamental design for a combined brush and container therefor, as shown and described.
